—Inventor—

William H. Meyer,
Cook & McCauley 1922.

UNITED STATES PATENT OFFICE.

WILLIAM H. MEYER, OF ST. LOUIS, MISSOURI, ASSIGNOR, BY MESNE ASSIGNMENTS,
TO THE DAVIS SEWING MACHINE COMPANY, A CORPORATION OF DELAWARE.

CLOTHES WRINGER.

1,402,244.

Specification of Letters Patent. Patented Jan. 3, 1922.

Application filed February 7, 1920. Serial No. 357,051.

To all whom it may concern:

Be it known that I, WILLIAM H. MEYER, a citizen of the United States of America, a resident of the city of St. Louis, in the 5 State of Missouri, have invented certain new and useful Improvements in Clothes Wringers, of which the following is a full, clear, and exact description, reference being had to the accompanying drawings, 10 forming a part of this specification.

This invention relates to improvements in clothes wringers, one of the objects being to provide a strong and simple wringer structure. Another object is to produce a 15 simple releasing device whereby the pressure at the wringer rolls may be easily and quickly released.

Fig. I is a front elevation illustrating a wringer embodying the features of this invention.

Fig. II is a vertical section on the line II—II, Fig. I.

Fig. III is a section on the line III—III, Fig. I.

Fig. IV is a perspective view of a pressure bar member, showing a releasing lever mounted thereon.

Fig. V is a perspective view of one of the bar sections constituting a latch device for 30 locking the pressure bar to the wringer frame.

To illustrate the invention I have shown a wringer frame comprising upright side members 1 forming housings for the bearings 2 in which the wringer rolls 3 and 3^a are rotatably mounted. The wringer frame also includes horizontally disposed upper members 4 integrally connected to the members 1, said upper members being provided 35 with longitudinal recesses 5. 4' designates caps secured to the end portions of the upper members 4.

Compression springs 6 are interposed between the upper bearings 2 and a tie bar 45 3'. Screws 7, acting upon the end portions of the tie bar 3', may be adjusted to vary the pressure of the springs 6. These springs allow the upper roll 3 to move toward and away from the lower roll, and they tend to 50 force the upper roll into engagement with the lower roll. The screws 7 extend through comparatively large openings 8 in the caps 4', but they are not secured in the caps, the openings 8 being large enough to permit the 55 screws to move vertically.

To illustrate the preferred form of the invention, I have shown a sectional pressure bar adapted to be broken longitudinally to release the springs 6, thereby allowing the upper wringer roll 3 to freely move away 60 from the lower roll. This sectional bar comprises a main bar member A, which may be channel-shaped in cross section, and side bar members B between which the bar A is interposed. Tongues 9, extending from 65 the end portions of the bar members B, extend through openings in the bar member A so as to pivotally interlock the bar members. The lower margins 10 of the bar members B extend into the recesses 5 so as to 70 interlock the sectional pressure bar with the wringer frame. An operating handle 11, pivoted at 12 to the bar member A, is provided with a forked end which straddles the bar members A and B to retain said bar 75 members in the positions shown in Figs. II and III.

Each end of the main bar member A is provided with nuts 13, which are threaded to receive the screws 7. It will therefore 80 be understood that the pressure exerted by the springs is transmitted through the screws 7, and thence to the main bar member A, and that this pressure tends to move the sectional bar vertically. However, when 85 the sectional bar is interlocked with the wringer frame, as shown in Figs. II and III, it cannot be forced upwardly by the spring pressure. To release the pressure, it is only necessary to strike the forked lever 90 11 so as to release its forked ends from the bar members B, thereby permitting said members B to swing on the pivots formed by their tongues 9, so as to release their lower margins 10 from the recesses 5 in the 95 wringer frame. The springs 6 will then force the sectional pressure bar upwardly until the ends of bar member A strike the caps 4'. The sectional pressure bar is thus broken longitudinally and unlocked from 100 the frame so as to relieve the spring pressure.

The sectional pressure bar is confined between the top members 4 of the wringer frame, as shown in Figs. II and III, so that 105 the bar members B are not released from the bar member A when the sectional bar is thrown upwardly, and this sectional bar can be easily restored by forcing it downwardly until its lower margins engage the bottom 110

walls of recesses 5 and slide into said recesses. After the bar has been restored it can be locked by restoring the operating lever 11.

5 I claim:

1. In a wringer, a frame, a pair of rolls, yielding means for forcing one of said rolls toward the other, a sectional pressure bar whereby said yielding means is held under pressure, said sectional pressure bar including sections pivotally secured together, the pivot being lengthwise of the sectional pressure bar, and said sectional bar being breakable longitudinally at the pivot in response to the pressure of said yielding means, and an emergency releasing device cooperating with said pressure bar to prevent longitudinal breakage thereof.

2. In a wringer, a frame, a pair of pressure rolls, yielding means for forcing one of said rolls toward the other, a sectional pressure bar interlocked with said frame to retain said yielding means under pressure, said sectional pressure bar including vertically movable sections pivotally secured to each other, the pivot being lengthwise of the bar, and said bar being breakable longitudinally at the pivot to unlock the sectional bar from said frame, and an emergency release preventing breakage of said sectional pressure bar.

3. In a wringer, a frame, a pair of pressure rolls, yielding means for forcing one of said rolls toward the other, a longitudinally breakable sectional pressure bar comprising latch sections interlocked with said frame and a bar section through which the pressure of said yielding means is transmitted to said latch sections, said bar section being pivotally secured to said latch sections, and an emergency release device comprising a lever straddling said bar section and latch sections to prevent longitudinal breakage of said sectional pressure bar.

4. In a wringer, a frame, pressure rolls, 45 yielding means for forcing one of said pressure rolls toward the other, a pressure bar to retain the yielding means under pressure, latch members extending from opposite sides of said pressure bar whereby said pressure bar is locked to said frame, said pressure bar being interposed between said latch members, and an emergency releasing device mounted on said pressure bar and acting upon said latch members to prevent their 50 55 displacement.

5. In a wringer, a frame, pressure rolls, yielding means for forcing one of said pressure rolls toward the other, a pressure bar to retain the yielding means under pressure, 60 latch members pivoted to said pressure bar and interlocked with said frame, said pressure bar being interposed between said latch members, and an emergency releasing device comprising a lever pivotally mounted 65 on said pressure bar and provided with a forked end embracing said latch members to prevent displacement of said pressure bar.

6. In a wringer, a frame, pressure rolls, 70 yielding means for forcing one of said pressure rolls toward the other, a pressure bar to retain the yielding means under pressure, latch members comprising bar sections arranged longitudinally of said pressure bar 75 and pivotally interlocked with the ends thereof, said frame being recessed to receive said latch members and the latter being extended into the recessed portions of the frame to prevent displacement of said pressure bar, 80 and an emergency releasing device pivotally mounted on said pressure bar and straddling said pressure bar and latch members to prevent displacement of the latch members.

In testimony that I claim the foregoing 85 I hereunto affix my signature.

WILLIAM H. MEYER,
